UNITED STATES PATENT OFFICE

FRANK C. BURTON, OF CHICAGO, ILLINOIS, ASSIGNOR TO GRIGSBY-GRUNOW COMPANY,
OF CHICAGO, ILLINOIS, A CORPORATION OF ILLINOIS

DESIGN FOR A RADIOCABINET

Application filed February 14, 1929. Serial No. 30,051. Term of patent 7 years.

To all whom it may concern:

Be it known that I, FRANK C. BURTON, a citizen of the United States, residing at 431 South Wabash Avenue, Chicago, Illinois, have invented a new, original, and ornamental Design for a Radiocabinet, of which the following is a specification, reference being had to the accompanying drawing, forming part thereof.

In the drawings:

Fig. 1 is a perspective view, showing the front and one side of the radiocabinet with the front door closed, and

Fig. 2 is a similar view taken at a different angle, but with the front door opened.

I claim:

The ornamental design for a radiocabinet as shown.

FRANK C. BURTON.
